UNITED STATES PATENT OFFICE

NOZZLE FOR SAND BLAST MACHINES

oy W. Weir, Chicago, Ill., assignor to Mott Sand
Blast Manufacturing Company, Chicago, Ill., a
corporation of Illinois

Application March 5, 1930, Serial No. 433,211

3 Claims. (Cl. 51-11)

The object of the present invention is the provision of a novel form of nozzle for sand blast machines which is highly economical and of greater durability than those ordinarily employed.

The common form of nozzle, which is made of low-resistance metals, quickly wears out. As generally used, its life is from one to four hours. Changing these nozzles, when worn, entails the waste of much time due to the necessity for shutting down, substituting new nozzles, and again getting started. Wear on these nozzles, which are relatively long, occurs mostly beyond the converging point, which latter is within the nozzle bore, the nozzle becoming worn out from the converging point to the discharge end before wear at the inlet is sufficient to give any trouble.

To attain the purpose of the present invention the latter seeks to provide a nozzle structure having a relatively broad, blunt discharge end, with an appropriate discharge opening therein so proportioned with respect to the diameter of the discharge end as to cause the sand or other abrasive to dam up in rear of the discharge end so as to be penetrated by the air, and thereby form an internal conical sand nozzle with its converging point outside of the discharge end of the nozzle structure. Thus, the "vena contracta" or converging area is outside the discharge opening of the nozzle structure, and not within the bore of the latter, avoiding wear on the nozzle due to the diverging of the abrasive from the converging area and the expansion and rebound against the sides of the nozzle.

35 Furthermore, by the form and arrangement of nozzle contemplated by the present invention economy of use of expensive metal alloys in the construction of the nozzle may be effected, thus enabling the employment of high-resistance alloys in the manufacture of the nozzle and prolonging the life of the nozzles over those formed of low-resistance metals solely.

Other objects of the invention will appear as the nature of the improvements is better understood, the invention consisting substantially in the novel construction, combination and arrangement of parts hereinafter fully described, illustrated in the accompanying drawing, and finally pointed out in the appended claims.

50 In the drawing

Fig. 1 is a longitudinal sectional view of a blast nozzle constructed in accordance with the present invention;

Fig. 2 is a face elevation thereof viewing the
55 same at the discharge end;

PATENT OFFICE

BLAST MACHINES

**Assignor to Mott Sand
Company, Chicago, Ill., a**

930, Serial No. 433,211
(Cl. 51-11)

Fig. 3 is a detail elevation of one of the closure disks of the nozzle, and

Fig. 4 is a similar view of the perforated disk nozzle or mouthpiece.

Referring in detail to the accompanying drawing, the numeral 10 designates the nozzle holder. It is in the form of a sleeve or tube, and one of its ends is threaded, as at 11, to provide for the attachment of a supply pipe or hose by which the abrasive-propelling agent, such as compressed air, is fed to the nozzle. The end of the holder 10 opposite to the threaded end 11 is enlarged to form a discharge head 12 the face of which is flat. Due to the formation of the head 12 the bore of the holder is enlarged diametrically, thereby forming a magazine chamber 13 at the interior of the holder. This chamber communicates with an opening 14 in the head 12, which opening is in line with the bore of the holder 10, but of greater diameter than such bore.

The head 12 has exterior screw threads 15 formed thereon, and mounted on said discharge head 12 is a follower cap 16 which is interiorly screw-threaded, as at 17, to engage with the threads 15 of the head 12. At the outer edge of the follower cap 16, or that edge which is most remote from the head 12 when the cap 16 is assembled on said head, is provided an inwardly-extending flange 18. This flange affords a centrally-disposed opening 19 at the outer edge of the follower cap, which opening is of greater diameter than the opening 14, but less than the diameter of the head 12.

Arranged between the flange 18 of the cap 16, and resting against the flat outer end of the discharge head 12, is a pair of flat closure disks 20. The flange 18 bears against these disks and, when the cap 16 is screwed upon the head 12, said flange clamps the disks 20 in firm contact with the flat face of the discharge head 12. Each of the disks 20 is provided with a centrally-disposed opening 21 surrounded by a countersunk portion 22. The faces of the disks 20 in which the countersunk portions 22 are formed abut each other, and these countersunk portions cooperate to form an annular recess about the openings 21 in which is positioned a perforated disk nozzle 23.

The disks 20 may be formed of any suitable material, such as cold-rolled steel, but the disk nozzle 23 is formed of a metal alloy of such character as to give high resistance to the abrasive agent or material which is passed through the nozzle. The disk nozzle 23 is loosely received in the recess formed between the disks 20 so as to be readily removable therefrom, and replaceable by a new 55

one in the event that replacement is required. The disks 20 also are removable from the nozzle structure, the only securing means being the follower cap 16 and its flange 18 in clamping cooperation with the head 12.

With the parts assembled as illustrated in Fig. 1, it is apparent that a distinct chamber, such as designated by the numeral 13, is formed at the interior of the nozzle holder adjacent to the disks 20. In the passage of the sand or other abrasive material the disks 20 cause the sand to dam up in the chamber 13. As the air penetrates the sand, in order to escape through the perforated disk nozzle 23, a conical nozzle of the sand or other abrasive will be formed within the chamber 13, as conventionally illustrated at 24 in Fig. 1, with its converging point outside of the nozzle structure. This positions the "vena contracta" or converging area outside the discharge opening, and not within the bore of the nozzle. Due to this, wear of the abrasive on the interior of the nozzle is reduced to a minimum, and such wear as occurs at the inlet is at a slow rate. Thus, the herein-described nozzle affords a high degree of efficiency. Its body portion or holder, which may be made of ordinary metal, is free from wear, the perforated disk nozzle 23 being the portion subjected in the main to the action of the abrasive. This being a relatively small part permits the same to be made of high-resistance alloys, so as to resist wear, thereby attaining the high degree of efficiency for the nozzle above referred to. The life of the nozzle is prolonged and the disk nozzle 23 may be readily replaced at small expense with facility and ease when such is required. The nozzle avoids the frequent renewals incident to the use of nozzles of the form now commonly employed.

I claim:

40 1. A nozzle for use in a sand blast machine, comprising a tubular holder enlarged at one of its ends to form a head provided at its interior with a chamber, said chamber being of greater diameter than the bore of the holder, said head 45 having a flat face wherein a discharge opening is

formed, said discharge opening communicating with said chamber, whereby the abrasive material is caused to form itself into an internal nozzle within the tubular holder and at the discharge end of the nozzle and the converging point thereby located beyond the discharge end of the nozzle.

2. A nozzle for use in a sand blast machine, comprising a body portion having a chamber at its discharge end and an opening in communication with said chamber, a plurality of closure disks arranged over said opening, said disks having aligned openings in communication with said chamber, a removable perforated disk nozzle arranged between said closure disks at the openings thereof, and means for holding said disks in engagement with the body portion to close the opening thereof which is in communication with the chamber of the head, said closure disks causing the abrasive material to form itself into an internal nozzle within the body portion and at the discharge end of the nozzle and thereby to locate the converging point beyond the discharge end of the nozzle.

3. A nozzle for use in a sand blast machine, comprising a tubular holder enlarged at one of its ends to form a head provided at its interior with a chamber, said head having a flat face, a plurality of flat disks cooperating with the flat face of the head and serving to close the chamber formed in the latter, said disks being provided with aligned openings in communication with said chamber, a perforated disk nozzle interposed between said disks and providing a discharge opening through which the abrasive is adapted to pass, said perforated disk nozzle being formed of high-resistance material, and means cooperating with said head for holding the closure disks in engagement with the head, the relation of the closure disks to said chamber causing the abrasive material to form itself into an internal nozzle within the tubular holder and to locate the converging point beyond the discharge end of the nozzle.

ROY W. WEIR.
